Primary Examiner — Zenia I Bennett(74) Attorney, Agent, or Firm — Heslin Rothenberg Farley & Mesiti, P.C.(57) CLAIM

The ornamental design for a band for a hair piece, as shown and described.

DESCRIPTION

FIG. 1 is a side perspective view of the band for a hair piece comprising my new design;

FIG. 2 is a front perspective view of the design of FIG. 1;

FIG. 3 is a rear perspective view of the design of FIG. 1;

FIG. 4 is a side elevational view of the design of FIG. 1;

FIG. 5 is another side elevational view of the design of FIG. 1;

FIG. 6 is a top perspective view of the design of FIG. 1; and, FIG. 7 is a schematic applied view of the band for a hair piece in use.

The broken lines shown in the drawings illustrate portions of the band for a hair piece that form no part of the claimed design. The broken lines in FIG. 7 illustrate environment in the form of a user of the band for a hair piece, with this environment forming no part of the claimed design. The surface contour lines in the drawings illustrates the contour of the claimed design and is not a claimed surface pattern.
